UNITED STATES PATENT OFFICE.

FRANK P. MURPHY AND OLIVE V. MURPHY, OF SMITHTON, PENNSYLVANIA.

STOPCOCK FOR FUEL TANKS.

Application filed February 21, 1924. Serial No. 694,277.

To all whom it may concern:

Be it known that FRANK P. MURPHY and OLIVE V. MURPHY, citizens of the United States, residing at Smithton, in the county of Westmoreland and State of Pennsylvania, have invented certain new and useful Improvements in Stopcocks for Fuel Tanks, of which the following is a specification.

The present invention relates to a stopcock for fuel tanks primarily intended for use on gasoline tanks on automobiles, and trucks.

The main object of the invention is to provide a device for effectively closing the supply of gasoline to the carburetor in order that when the owner of the automobile leaves it unattended and closes his valve, no unauthorized person can start the automobile, because no gasoline is available for this purpose. Another object of the invention is to prevent the stealing of gasoline from the tank, which is also effected, by the same stopcock.

It happens frequently when an automobile is left unattended that the owner finds on his return that the gasoline has been stolen so that he has no means of starting his engine to proceed on his journey. It also frequently happens that not only the gasoline is gone but also the car itself has been stolen, all because ordinarily no means have been provided for closing the gasoline supply from the tank. The present invention now aims at preventing such theft of the gasoline, and of the automobile and to accomplish this by very simple means.

In the accompanying drawing:

Figure 1 is a vertical section of a gasoline tank with the device installed, and

Figure 2 is a transverse section along line 2-2 of Figure 1.

In the drawing, reference numeral 10 represents a gasoline tank of the usual cylindrical shape at the bottom of which is attached, in the usual manner, a sediment bulb 11, provided at its lower end with a drain cock 12 of conventional construction. On one side of the bulb is seen the usual feed pipe 13 leading to the carburetor of the engine.

The upper end of the bulb 11 has an enlarged head 14 which has an external thread 15 fitting in an external boss 16 at the bottom of the tank. The upper end of the head 14 has still another threaded portion which is smaller in diameter than the threaded

part 15 so that a shoulder is formed on the head as at 18. Against this shoulder 18 is drawn up tightly upon the thread 17 a tube 19 of a length substantially the same as the 60 diameter of the tank.

Diametrically opposite to the boss 16 the tank is provided at its upper side with an internally directed collar 20 having a thread 65 adapted to receive the upper threaded end of the tube 19. The upper end of the tube is closed by a plug 21 which is preferably threaded in the tube to form a tight joint. This plug has an internal thread adapted to receive an upper threaded portion 22 of 70 a valve stem 23 which is preferably provided with a flat or square tip 24 adapted to receive a small hand wheel 25. This wheel may be detachably mounted on the tip 24 so that it may be easily removed by the owner, or a strap 26 with a padlock or the like, 75 may be provided for locking the wheel in closed position.

The stem 23 extends downwardly through the tube 19 and terminates with a conical 80 valve head 27 for which a correspondingly shaped seat 28 is furnished in the upper part of the head 14. The seat 28 preferably opens at a comparatively low point in the bulb through the pipe 29 in the usual manner. The tube 19 is provided with a plurality of 85 perforations 30, see Fig. 2, in order to admit gasoline from the tank into the valve seat 28 into which the perforations open.

Before starting his engine the operator 90 turns the small hand wheel 25 sufficiently to raise the valve head 27 out of its seat 28 into the approximate position indicated in Fig. 1. In this position the valve permits gasoline from the tank surrounding the tube 19 95 to enter through the apertures 30 and pass through the seat 28 into the sediment bulb 11. From there the gasoline is drawn in the usual manner into the carburetor through the feed pipe 13.

When leaving the automobile the operator turns the hand wheel 25 until the valve head 27 is firmly seated in the head 14 thus preventing any gasoline from entering the sediment bulb. By now removing the hand 100 wheel 25 or locking it with a padlock or other similar device, the operator makes sure that his automobile cannot be stolen because all the gasoline available to be turned into the carburetor to start the engine is found in the bulb. Accordingly, if 105 an unauthorized person should attempt to

start the automobile this would be impossible on account of the lack of gasoline for the engine.

On the other hand, somebody that does not possess a key or a hand wheel 25 cannot drain the gasoline tank 10 through the drain cock 12 as only the gasoline contained in the small sediment bulb 11 would pass out and part of which would be unsuitable for use.

10 Another advantage attained by this device when fitted on an automobile is that the stopcock can be easily closed without stooping or crawling under the automobile when some repair work has to be done on the 15 engine.

It will be evident that this device may be installed not only on new automobiles but also on old ones as the stop cock with all the parts pertaining thereto are furnished as 20 assembled complete so that they can be screwed into position from the under side of the tank and all that is necessary to provide on an old tank would be a boss or collar 20 in the upper part of the tank opposite the boss 16 25 in the bottom thereof.

A very important advantage of the present invention is that, if fire should occur on an automobile, or truck fitted with this device, the gasoline supply may immediately 30 be cut off from the engine without danger to the operator as he does not have to crawl under the automobile to do so. In this manner he saves himself and others from

serious injury, the possible explosion of the gasoline tank and the total destruction of 25 the automobile, which would otherwise be an almost certain consequence.

Having thus described the invention, what is claimed as new is:

A stopcock for fuel tanks comprising internally threaded collars secured respectively at the top and bottom of the tank, a head threaded into the threaded portion of the collar at the bottom of the tank and having a reduced upper end within the tank, a downwardly extending neck on the head terminating with a sediment bulb, a discharge pipe on said neck, a valve seat formed in the upper end of the head, a tube extending diametrically across the tank and having its upper end threaded into the collar at the top of the tank and its lower end secured around the upper reduced end of the head and bearing upon the head at the base of said reduced end, the tube being provided with 55 apertures adjacent the valve seat for admitting fuel thereto from the tank and the upper end of the tube being closed, a valve fitting the seat, and a valve stem rising from the valve and having threaded engagement 60 with the closed upper end of the tube.

In testimony whereof we affix our signatures.

FRANK P. MURPHY. [L. S.]
OLIVE V. MURPHY.
